[57] CLAIM

The ornamental designs for a truck tailgate fairing, as shown and described.

DESCRIPTION

FIG. 1 is a rear perspective view of a truck tailgate fairing showing my new design;

FIG. 2 is a front perspective view thereof;

FIG. 3 is a top plan view thereof;

FIG. 4 is a rear elevation view thereof;

FIG. 5 is a front elevation view thereof;

FIG. 6 is a right side elevation view thereof;

FIG. 7 is a left side elevation view thereof; and,

FIG. 8 is a bottom plan view thereof.

The broken line showing of a truck tailgate in FIGS. 1, 2, 4 and 5 of the drawing is for illustrative purposes only and forms no part of the claimed design.

FIG. 1.FIG. 2.FIG. 3.FIG. 4.

FIG. 5.FIG. 6.FIG. 7.FIG. 8.
